US00D400539S

United States Patent [19]

Hippen

[11] Patent Number: Des. 400,539

[45] Date of Patent: **Nov. 3, 1998

[54] **REMOTE CONTROLLER WITH A CRYSTAL MONITOR**

[75] Inventor: **Jan Hippen**, Portland, Oreg.

[73] Assignee: **Kenwood Corporation**, Tokyo, Japan

[**] Term: **14 Years**

[21] Appl. No.: **52,405**

[22] Filed: **Mar. 29, 1996**

[51] LOC (6) Cl. **14-03**

[52] U.S. Cl. **D14/218**

[58] Field of Search **D14/218, 217; D10/104, 106; D13/168; 348/734; 455/151.1, 151.2, 151.3, 151.4, 352-355**

[57] CLAIM

The ornamental design for an remote controller with a crystal monitor, as shown and described.

DESCRIPTION

FIG. 1 is a perspective view of my design as seen from the right front and above;

FIG. 2 is a front elevational view of my design;

FIG. 3 is a rear elevational view of my design;

FIG. 4 is a right side elevational view of my design;

FIG. 5 is a bottom plan view of my design;

FIG. 6 is a top plan view of my design;

FIG. 7 is a perspective view corresponding to that of FIG. 1, but showing the design as it appears in use on an audio/visual amplifier, the audio/visual amplifier being shown in phantom outline; and,

FIG. 8 is a right side elevational view of my design.

The broken line environmental showing is for illustrative purposes only and does not form part of the claimed design.
